UNITED STATES PATENT OFFICE.

NICHOLAS STEFFENS, OF NEW YORK, N. Y.

DESIGN FOR A FLOWER-FRAME.

SPECIFICATION forming part of Design No. 20,638, dated March 24, 1891.

Application filed February 5, 1891. Serial No. 380,361. Term of patent 7 years.

To all whom it may concern:

Be it known that I, NICHOLAS STEFFENS, a citizen of the United States, residing at New York, in the County and State of New York, 5 have invented and produced a new and original Design for Flower-frames, of which the following is a specification.

This invention relates to a flower-frame consisting of the details set forth in the following specification and claim and illustrated in the annexed drawing, which shows a perspective view of the design.

The leading feature of the design consists in a horizontal base provided centrally between its ends with a pillow-like elevation, in 15 rear of which rises a pair of upright posts, between which are suspended gates ajar.

The letter A indicates a horizontal base provided centrally between its ends with a pillow-like elevation B, in rear of which rises a 20

pair of upright posts C. The gates D are suspended ajar between the upright posts C. The top portions of the posts are joined to form an apex or heart-shaped projection E.

What I claim as new, and desire to secure 25 by Letters Patent, is—

The design for a flower-frame, consisting of a horizontal base provided centrally between its ends with the pillow-like elevation B and rear upright posts C, rising from the base, 30 and between which are suspended gates ajar, substantially as shown and described.

In testimony whereof I have hereunto set my hand in the presence of two subscribing witnesses.

NICHOLAS STEFFENS.
